UNITED STATES PATENT OFFICE

JENS N. JACOBSEN, OF ALAMEDA, CALIFORNIA, ASSIGNOR TO THE PFAUDLER CO., OF ROCHESTER, NEW YORK, A CORPORATION OF NEW YORK

HEAT-TRANSFER APPARATUS

Application filed March 13, 1928. Serial No. 261,348.

This invention relates to a heat transfer apparatus and has for its principal object the provision of such an apparatus which is more satisfactory, efficient and dependable in operation than others heretofore known.

Another object of the invention is the provision of a heat transfer apparatus in which the material to be treated can be heated to a very high temperature or cooled to a low temperature without becoming caked on the walls of the apparatus to such an extent as to interfere seriously with the transfer of heat through the walls.

A further object of the invention is the provision of heat transfer apparatus which may be used for cooling an ice cream mixture or other similar material in which means is provided for scraping the walls of the apparatus during the operation thereof, such means preferably consisting of a spirally or helically formed strip of material which is rotated by the movement of the fluid through the apparatus.

To these and other ends the invention relates in certain improvements and combinations of parts, all as will be hereinafter more fully described, the novel features being pointed out in the claims at the end of the specification.

30 In the drawings:

Fig. 1 is a longitudinal section taken approximately centrally through an apparatus constructed in accordance with a preferred embodiment of the invention:

35 Fig. 2 is a view of the cover member or door used at one end of the apparatus;

Fig. 3 is a view of the cover member or door used at the other end of the apparatus;

Fig. 4 is a transverse sectional view taken approximately on line 4-4 of Fig. 1; and

Fig. 5 is a longitudinal sectional view through the tubes used in the apparatus.

The same reference numerals refer to the same parts through the several views.

45 Referring now to the drawings, there is illustrated a heat transfer apparatus including a drum 11 having manifolds 12 and 13 at the ends thereof, and an outer shell member 14 surrounding the inner drum 11 and the manifolds, as illustrated in Fig. 1. The

space between the inner drum 11 and the shell 14 is preferably filled with some suitable lagging or heat insulating material, such as asbestos.

Removably mounted within the drum is a tube assembly including tubes 16 having their ends supported in headers 17 and 18, the latter having its periphery secured to an annular flange on the manifold 13 by means of suitable bolts 19. The other header 17 is of a smaller diameter than the manifolds, so that the entire tube assembly may be removed from the drum as a unit by unfastening the bolts 19 and drawing the tubes and headers leftwardly when viewed as in Fig. 1. An annular flange formed on the header 17 has a snug sliding fit within an internal flange 20 on the manifold 12. A ring of packing material 21 surrounds the header 17 and is pressed against the manifold 12 to form a tight joint by means of the annular member 22 secured in place by bolts 23 threaded into the manifold 12, all as shown in Fig. 1.

This jointed arrangement between the tube assembly and the drum at the right hand end of the apparatus not only permits easy removal of the tubes as a unit, but also provides an expansion joint so that the tubes may expand or contract relative to the drum, without creating excessive stresses.

50 Cover members such as the doors 25 and 26 are placed over the headers at the right and left ends of the apparatus, these cover members having machined surfaces in contact with machined surfaces on the headers, so that tight joints are provided without the use of gaskets. Each cover plate has a series of cavities formed therein, the cavities being so shaped that they form passageways connecting the ends of two adjacent tubes to each other. In this manner, all of the tubes are connected in series, so that material forced into one end of the first tube will travel through it, then back through the next tube, forward again through the next succeeding tube, and so on. Obviously the connections could be varied so that all of the tubes could be connected in multiple or parallel, or some could be in series and some in multiple or parallel. The number of tubes used, as well as

90

95

100

the manner in which they are connected, would depend on the kind of material to be treated in the apparatus, and the extent to which the material was to be cooled or heated.

5 The cover members 25 and 26 may be hinged to the headers 17 and 18 if desired, and may be provided with latches for holding them in place. Preferably they are secured in position also by pivoted bolts 27 mounted on the headers, these bolts having nuts 28 which press against split lugs 29 on the cover members.

10 One of the cover members, such as 25, has threaded openings 30 and 31 extending therethrough, into which pipes 32 and 33 may be screwed. One of these pipes is connected to a source of supply of material to be treated, this source preferably including means for forcing the material into the tubes with sufficient pressure so that it will pass through the tubes and out of the other pipe. The material to be treated may be gaseous, liquid, semi-liquid, or of any form sufficiently plastic to pass through the tubes when under pressure.

15 20 25 The term "fluid", as used in this specification and in the accompanying claims, is used in its generic sense, and is intended to include any materials of the kind above mentioned.

30 Suitable connections are provided for circulating a treating medium around the tubes 16 within the drum 11. Such connections may comprise an inlet pipe 35 leading to the manifold 12. The treating medium (for example, water) enters the manifold through 35 this pipe 35, and passes thence through the oblique slots 36 into the drum 11. The angular arrangement of these entrance slots 36 gives the treating medium a rotating or swirling movement within the drum, thus 40 thoroughly agitating the medium and bringing various parts of it into contact with the tubes 16, so that the transfer of heat is expedited.

45 The treating medium may then pass out of the drum through the slots 37 in the manifold 13, and may leave this manifold by way of a pipe 38. The exit slots 37 may be oblique, like the slots 36, the obliquity being either in the same direction as or in the opposite direction to that of the slots 36; or they may 50 extend radially through the wall of the manifold.

55 It will be understood that the treating medium circulated within the drum 11 may be a gas, liquid, or semi-liquid, the mention of water being simply by way of example. When a liquid medium is used, air is apt to collect at the top of the drum, and a vent connection is therefore provided to remove it, this connection comprising a pipe 40 leading from the top of the drum to the exit pipe 38, as shown in Fig. 1. A drain pipe 41 may also be provided at the bottom of the drum 11, this drain pipe being controlled by a valve 42.

70 The apparatus above described is fairly satisfactory for use at moderate temperatures. It is found in practice, however, that if such an apparatus be used to raise a material to a rather high temperature, the material being treated has a tendency to burn or cake on the walls of the tubes 16. Also, if the material being treated is lowered to a low temperature, it has a tendency to freeze and form cakes on the tube walls. In both 75 of these cases, the thermal efficiency of the apparatus is greatly reduced by the layer of material deposited on the walls, and the cross-sectional area of the tubes is also reduced, so that less material can be forced therethrough. In order to overcome these 80 difficulties, and to provide an apparatus which can be used, for example, for cooling an ice cream mixture, means is provided for agitating the material to be treated and for automatically scraping the interior walls of the tubes 16 while the apparatus is in operation, this means preferably being operated automatically by movement of the material 85 to be treated through the tubes.

90 This scraping means comprises a member 50 within each of the tubes 16. Each member 50 is formed of a strip of sheet material twisted into the form of a spiral, so that one or both edges of the strip extend along the tube in the shape of a helix. These twisted strips, in the embodiment shown, are made of a diameter very slightly less than the diameter of the tubes 16, so that the strips or spiral members are rotatable 95 within the tubes but will scrape practically all points of the circumference of the tubes when the strips are rotated.

100 The ends of each strip project from its tube and are provided with ball-like members 51 which contact loosely with the cover members 25 and 26. The ball-like members may rotate easily on the cover members with a minimum of friction and thus act as thrust bearings to prevent longitudinal movement 105 of the spiral members 50 while allowing rotary movement thereof. The members 50 which are in alinement with the pipes 32 and 33 may have thrust bearings comprising angular offset feet 52 adapted to contact with the ends of the pipes and to ride around on these ends as the spiral members are rotated.

110 Each of the spiral members 50 is twisted throughout its length in a single direction, 110 as shown in Fig. 5. As the material to be treated is forced through the tubes 16, it will tend to rotate each of the spiral members, and the speed of the resulting rotation 115 will depend on the friction between the spiral member and the tube, on the rate of travel of the material through the tube, and on the viscosity or consistency of the material being treated. Under some conditions, 120 the spiral members 50 may not rotate at all 125 130

but may remain stationary within the tubes. They then act as baffles tending to agitate the fluid or circulate it circumferentially of the tubes, and this tends to scour the walls of the tubes as well as to insure contact of all portions of the fluid with the walls. Thus there is considerable advantage in the use of these spiral strips even when they do not rotate, though the best results are obtained when the strips do revolve in the tubes.

In the case of an ice cream mixture which is being cooled to a comparatively low temperature in an apparatus of this kind, the rotation of the cleaning members or spiral strips 50 serves to prevent freezing of the mixture on the walls and to scrape away immediately any of the material which does tend to adhere to the tube walls. The rotation of the strips will also agitate the material within the tubes, thus mixing it thoroughly so that all portions of the material come into contact with the walls of the tubes during its passage therethrough. Thus the tubes will not become clogged as the temperature of the mixture falls, and the apparatus will continue to perform efficiently at temperatures much lower than those possible with apparatus not provided with cleaning and agitating members. Also, it may be used efficiently at high temperatures, since the rotating cleaning and agitating members will prevent the accumulation of scale or deposit on the inside walls of the tubes 16, due to the high temperatures used.

It will now be seen that there has been provided a heat transfer apparatus which is far more practical and efficient than those heretofore used, especially when the material being treated is to be raised to comparatively high temperatures or cooled to comparatively low temperatures. Also, an effective automatic cleaning means has been provided for scraping the walls of the tubes to prevent accumulation of solid material thereon.

While one embodiment of the invention has been disclosed, it is to be understood that the inventive idea may be carried out in a number of ways. This application is therefore not to be limited to the precise details shown, but is intended to cover all variations and modifications thereof falling within the spirit of the invention or the scope of the appended claims.

55 I claim as my invention:

1. In a cooling apparatus, the combination with a container for holding a treating medium, of a plurality of conduits within said container, said conduits providing a passageway for an ice cream mixture, a unidirectional spiral strip rotatably mounted within each of said conduits and in contact with the side walls thereof, and means for preventing longitudinal movement of said strips while allowing rotation thereof, so that

passage of said ice cream mixture through said conduits will rotate said spiral strips and scrape the walls of said conduits to prevent accumulation of frozen material thereon.

2. In a heat transfer apparatus, the combination with a pair of headers, of a plurality of conduits extending between said headers, a cover member on one of said headers, a spirally twisted strip loosely mounted within each of said conduits, a ball upon the end of each of said strips, said balls being adapted to contact with said cover member to provide thrust bearings for preventing longitudinal movement of said strips while allowing rotary movement thereof, and means for forcing material through said conduits to rotate said strips automatically to scrape the walls of said conduits during the passage of said material.

3. In a heat transfer apparatus, the combination with a conduit for the passage of liquid, of means automatically and continuously operated by the movement of said liquid for scraping substantially the entire area of the walls of said conduit to prevent the formation of deposits thereon.

4. In a heat transfer apparatus, the combination with a casing for containing a treating fluid, of a conduit extending through said casing for passage therethrough of liquid to be treated, and a spiral cleaning member normally retained within said conduit to be rotated substantially continuously during passage of liquid to be treated through said conduit by the action of such liquid on said member.
